UNITED STATES PATENT OFFICE.

JOHN F. O'ROURKE, OF NEW YORK, N. Y.

MEANS FOR GROUTING MASONRY.

Application filed August 28, 1919. Serial No. 320,345.

To all whom it may concern:

Be it known that I, JOHN F. O'ROURKE, a citizen of the United States, and resident of New York city, in the county of New York and State of New York, have invented certain new and useful Improvements in Means for Grouting Masonry, of which the following is a specification.

In grouting masonry the practice heretofore, so far as I am aware, has been to leave or make holes in the joints between the blocks and in the pointing of the joints, through which holes the grout was poured or forced into the joints. This involved many difficulties and much time and cost, and has often resulted in choking the joints with spawls and dirt so that the completeness of the grouting was a matter of doubt.

The object of this invention is to provide a ready and effective means for grouting joints in masonry comprising concrete blocks, terra cotta and other molded building material. I accomplish such object by forming passages in some of the blocks opening therethrough between the faces of the blocks and the joints between the blocks. Said passage may be fitted with a screw thread molded into the material of the block for convenience in attaching a grout pipe. Plugs may also be provided for closing the openings in the faces of the blocks.

Where joints between blocks are not open throughout from front to back, as in the case of tongue and groove joints between adjoining courses or rings, connections are provided to the joint on each side of the tongue or groove or other interruption. These may be independent passages opening to different parts of the joint or one passage may be connected to both such parts with openings into each so that both parts may be grouted in the same operation.

The grouting can be done at once whenever the joints in the face of the masonry are pointed, caulked or otherwise closed against the outflow of the grout through such joints. When joints are maintained at a minimum width sufficient to permit grout to flow from joint to joint until all are filled and no more can be forced through the supply pipe, my invention as applied to the grouting of concrete block tunnel linings or piers insures a monolithic construction.

Reference is to be had to the accompanying drawings forming part hereof, wherein—

Fig. 1 is a face view of a portion of a tun-

nel lining or arch comprising molded blocks embodying my invention, having spaced complemental projections and recesses on opposite faces;

Fig. 2 is a partly broken under side view thereof;

Fig. 3 is a detail of a lining or arch where-in the blocks have continuous intermeshing tongues and grooves;

Fig. 4 is a detail section;

Fig. 5 is a detail section illustrating the grout passage opening through the face of a block on opposite sides of an interruption along such face;

Fig. 6 illustrates a portion of a pier or column embodying my invention;

Fig. 7 is an enlarged detail section of a portion of a mold for blocks, illustrating means for forming the grout passages in molded blocks, and

Fig. 8 illustrates the block removed from the mold.

Similar numerals of reference indicate corresponding parts in the several views.

The blocks 1 may be of concrete, terra cotta or other material for molded building blocks, which may be made in any well known manner, as by charging the material for the blocks into suitable molds. The blocks may be of the class having projections 2 on one face and recesses 3 on another face, the recess of one block receiving the projection of an adjacent block. Said projections may be of such length from the corresponding face of the block compared to the depth of the recesses that when the blocks are laid in ring form or courses the joints 4 between the blocks will be appreciable in extent. Such an arrangement of blocks is set forth in U. S. Letters Patent issued to me Nov. 5, 1912, No. 1,043,348. Or the blocks may have grooves 3 continuous along one face to receive continuous tongues or projections 2 of adjacent blocks for uniting the blocks in lateral directions, in a well known manner. Any desired number of the blocks are provided with grout passages 7 that open through a convenient face of each such block, as at 7^a, for entrance of grout, and also open through the faces of such blocks at the corresponding joint 4, as at 7^b, for the exit of grout into the joints. The grout passages may open at 7^b through the faces of the blocks on either side of the projection, tongue or recess, or may open at 7^b through the faces of the blocks on opposite sides

of such projection, tongue or recess, a single passage 7 having two outlets 7^b, such as in Fig. 5. Each block, or any desired number of blocks, in a tunnel lining or other structure may have one or more of the passages 7 opening at 7^b through the face that will be at the joint between blocks. For tunnel linings the grout inlet openings usually will be in the inner faces of the blocks with the outlets 7^b in faces angularly disposed thereto. The later construction may be provided for arches and other structures. For solid masonry comprising molded blocks the grout inlet openings 7^a may be on the outer faces 15 of the blocks and the outlets 7^b in desired inner faces of such blocks, although the inlets 7^a may be on either face convenient of access and the outlets 7^b on either face of a block that opposes another block.

20 In Fig. 7 I have illustrated a means for producing the passages in the blocks when they are being molded. A wall 8 of the mold is provided with one or more holes 9 adapted to receive a plug or core 10 of desired dimensions, which plugs may have screw threads 11, preferably adjacent to the inner face of the wall 8. At 12 is a die or core within the mold, shown in tapering form inwardly and retained upon the mold board or wall 13 by a pin 14 preferably screwed into the mold board, and entering a hole in the die or core 12 to removably retain it in the mold. The inner end of die or core 12 is provided with a transverse bore or hole 15 35 registering with hole 9 and adapted to receive the inner end of plug 10, whereby the latter and the die 12 will be at an angle to each other when in the mold. With the mold parts assembled as shown in Fig. 7 the concrete or other material *a* will be charged into the mold in any suitable or usual way, and such material will envelop the plug 10 and die or core 12 within the mold to produce the passage 7 with its inlet 7^a and outlet 7^b 40 together with the threads 7^c at the grout receiving side of the block, as illustrated. After the material *a* has set or hardened, as desired, the plug 10 can be unscrewed, and by reason of the threads 7^c formed in the 45 material *a* by the threads 11 the removal of said plug from such material is facilitated. When the block is removed from the mold its passage will be substantially as shown in Fig. 8. The threads 7^c in the block 50 afford a simple means for the attachment to the block of a pipe or hose of a grout gun or machine.

After any desired number of the blocks have been set and when the joints between 60 the blocks have been pointed, caulked, or otherwise closed the grout pipe or hose may be connected to the inlet 7^a of a passage 7 of any such blocks to enable the grout to be forced into such joints 4 under pressure

by flowing through the material of the block from inlet 7^a through outlet 7^b, until the space between the blocks is completely filled with the grout. When the grout pipe or hose is removed from the inlet 7^a the latter may be closed by a suitable plug 70 screwed or forced therein.

A great advantage of my invention is that the grouting of the joints may be accomplished from faces of the blocks other than the joint faces, whereby access may be 75 readily had to the grout inlets without disturbing the pointing or caulking of the joints, and whereby such pointing or caulking may be continuous and intact throughout, without requiring holes or spaces in the pointing or caulking, thereby overcoming objections to the old methods of grouting joints and affording a more complete and secure grouting of the joints.

By the term building blocks as used herein I mean to include molded blocks of suitable material adapted for use for linings for tunnels, sewers and other conduits as well as for arches, piers, walls and floors, and all other structures or parts thereof 90 where such blocks are useful and the joints are to be grouted.

My invention is particularly applicable to so called dry masonry, or masonry in which the mortar does not completely fill the joints, and having parts of the joints of the masonry sealed with a pointing which may be of mortar or mastic or an asphaltum-like material, or a caulking of oakum or other material driven into the faces of the joints, 95 and by the word pointing as used herein I mean to include all of such or similar means to close the exterior portions of the joints.

Having now described my invention what I claim is:—

1. In a tunnel or conduit lining molded blocks having open joints therebetween, some of said blocks having passages opening at one end into the tunnel and opening at the other end into the joint between adjacent blocks, and a filling within said joints between the opening of said passages into the joints and the inner surface of the tunnel, said joints being open along the outer surface of the lining to permit grout to flow from said joints into any spaces surrounding the tunnel.

2. A building block having an interruption along a face and provided with a passage for grout having outlet openings through said face on opposite sides of the interruption, said passage having an inlet in another face.

Signed at New York city, in the county of New York and State of New York, this 26 day of August A. D. 1919.

JOHN F. O'ROURKE.
